UNITED STATES PATENT OFFICE.

RUSSELL A. HILL, OF ST. THOMAS, ONTARIO, CANADA.

COPY-HOLDER.

1,074,430.

Specification of Letters Patent. Patented Sept. 30, 1913.

Application filed August 17, 1912. Serial No. 715,592.

To all whom it may concern:

Be it known that I, RUSSELL A. HILL, a subject of the King of Great Britain, and a resident of St. Thomas, in the Province of 5 Ontario, Dominion of Canada, have invented a new and Improved Copy-Holder, of which the following is a full, clear, and exact description.

My invention has for its object to provide 10 a copy holder having pivoted arms with means for holding the arms normally in adjusted position, there being an additional member having arms pivoted to the first-mentioned arms, so that the member 15 may be moved relatively to the first-mentioned arms by a rod pivoted at one end relatively to the arms, and at the other end to the arms on the member at one side of the pivot point connecting the member with the 20 first-mentioned arms. With this construction the first-mentioned arms may be held in one position with the member held to support the copy in position to be conveniently read and when desired the first-mentioned 25 arms may be moved, when the rod will move the member relatively to the first-mentioned arms, so that the device will be in position to permit the typist to make notes on the member carried by the second arms. This 30 movement of the member will also permit the typist to conveniently reach over the device to make corrections on the typewriter when the device is disposed across the typewriter.

35 Additional objects of my invention appear in the following complete specification, in which the preferred form of my invention is disclosed.

In the drawings similar characters of reference 40 indicate corresponding parts in all the views, in which:

Figure 1 is a side elevation showing my device in position to support the copy so that it may be conveniently read; Fig. 2 is 45 a view showing the device moved so that the copy may be supported on the pivoted member to permit the typist to make notes; and Fig. 3 is a front elevation of Fig. 1.

By referring to the drawings it will be 50 seen that two base members 5 are provided, these base members being spaced apart, the arms 6 being pivoted to these base members 5 at the points indicated by the reference characters 7. In the base members 5 there are teeth 8, with which pins 9, which

extend inwardly from the arms 6, engage, so that the said teeth 8 engaging the pins 9, limit the movement of the arms 6 relatively to the base members 5.

Pivoted at the points 13 to the upper terminals 10 of the arms 6, there are arms 11, which form part of the member 12. Extending upwardly from the pivot points 13 the arms 11 have inwardly extending telescoping members 14, which connect one of 60 the arms 11 with its companion arm. The arms 11 extend downwardly below their pivot points 13, and to the lower terminals 15 of the arms 11 there are articulated the rods 16, the lower terminals of the rods 16 65 being pivoted to the base members 5 at the points 17. It will therefore be seen that when the arms 6 are moved relatively to the base members 5, the rods 16 will move the arms 11 on their pivots 13 and relatively to 70 the arms 6. By this means the arms 11 will be moved relatively to the arms 6, from the position shown in Fig. 1 of the drawings, to the position shown in Fig. 2 of the drawings. When the arms 6 are moved from the 75 position shown in Fig. 1 of the drawings to the position shown in Fig. 2 of the drawings. When the arms 11 are disposed in the position shown in Fig. 1 of the drawings, they 80 serve to support copy, which may be conveniently read by the typist, since the base members 5 may be disposed one at each side of the keyboard of the typewriter, and with the arms 6 extending upwardly therefrom. When the typist desires to make notes or to 85 reach over the top of the copy holder to make corrections, on the typewriter, the arms 6 are moved forward to the positions shown in Fig. 2 of the drawings, when the arms 11 will be moved by the rods 16 so that 90 the member 12 will be so disposed that a plate member may be supported thereon, and notes may be conveniently taken. It is also possible, when the member 12 is in this 95 position, to reach over the member to make 100 corrections on the typewriter.

Guides 18 are secured to the arms 6, and extend around the rods 16, to limit the movement of the rods 16 away from the said arms 6. The rods 16 may be freed from the 105 arms 11, when the member 12 may be folded between the arms 6. The arms 6 with the base members 5 may then be pushed toward each other telescoping the members 14 so that the device may be packed in very lit- 110

tle space. The arms 6 may also be adjusted relatively to each other to fit any size or kind of typewriter.

Having thus described my invention, I 5 claim as new and desire to secure by Letters Patent:

1. In a copy holder, two pivoted arms spaced apart, a member having two arms pivoted adjacent their lower ends to the first 10 arms, transversely telescoping arms connecting the second-mentioned arms, and rods pivoted at one set of ends to the second-mentioned arms, and at their other ends relatively to the arms.

15 2. In a copy holder, two base members normally free from each other and having projections, two arms pivoted to the base members, pins on the arms for engaging the projections to limit the movement of the 20 arms relatively to the base member, a member having two arms pivoted at their lower ends to the first arms, transversely telescoping

ing members connecting the second-mentioned arms, and rods pivoted at one set of ends to the second-mentioned arms, and at 25 their other ends to the base members.

3. In a copy holder, two base members normally free from each other, two arms pivoted to the base members, a member having two arms pivoted adjacent their lower 30 ends to the first arms, transversely telescoping members connecting the second-mentioned arms, and rods pivoted at one set of ends to the lower ends of the second-mentioned arms, and at their other ends to the 35 base members.

In testimony whereof I have signed my name to this specification in the presence of two subscribing witnesses.

RUSSELL A. HILL.
